UNITED STATES PATENT OFFICE.

EMMETT A. SAUNDERS, OF MISHAWAKA, INDIANA.

DESIGN FOR A BOOT.

46,548.

Specification for Design.

Patented Oct. 13, 1914.

Application filed July 14, 1914. Serial No. 850,993. Term of patent 14 years.

To all whom it may concern:

Be it known that I, EMMETT A. SAUNDERS, a citizen of the United States, residing in Mishawaka, in the county of St. Joseph, State of Indiana, have invented a new, original, and ornamental Design for a Boot, of which the following is a specification, reference being had to the accompanying drawing, forming a part thereof, in which the figure of the drawing is a side elevation of a boot showing my new design.

I claim:

The ornamental design for a boot, as shown.

EMMETT A. SAUNDERS.

Witnesses:

HENRY HASPER,
WOLDEMAR HAUPT.
